UNITED STATES PATENT OFFICE.

FREDERIC C. CROWE AND BENJAMIN H. DE HAVEN, OF PITTSBURGH, PENNSYLVANIA.

CORK-PULLER.

1,275,228.

Specification of Letters Patent. Patented Aug. 13, 1918.

Application filed August 4, 1916. Serial No. 113,152.

To all whom it may concern:

Be it known that we, FREDERIC C. CROWE and BENJAMIN H. DE HAVEN, citizens of the United States, residing at Pittsburgh, 5 in the county of Allegheny and State of Pennsylvania, have invented certain new and useful Improvements in Cork-Pullers, of which the following is a specification.

This invention relates to devices for extracting corks from bottles and other similar receptacles, and has more especial reference to an improved device of the character stated, whereby, the stopper will be pulled by suction means.

15 It is among the aims and objects of the invention, to eliminate the use of the ordinary form of extractor, which comprises an instrument insertible within the stopper, to which, when embedded within the stopper, 20 a pull of sufficient force, to cause the dislodgment of said stopper, is imparted.

This form of extractor is exceedingly objectionable, due to the manner in which the stopper is mutilated, rendering it unfit for 25 subsequent usage and oftentimes, forcing the same downwardly, into the bottle.

The nature of the invention, more explicitly set forth, may be stated briefly, to comprise a pump provided with suitable pistons 30 and having a cap member arranged upon the lower end thereof, the pump cylinder provided with a suction controlled valve arranged in the bottom thereof adjacent the top of the cap and operating means in the 35 form of a pair of pivotal jaws having suitable handles formed thereupon, one of which is engageable with the piston rods for actuating the same, while the remaining serve to support the pump cylinder.

40 The improvements in the details and arrangements of parts will be apparent from an inspection of the accompanying drawings, in connection with the specific description hereinafter contained, and wherein the 45 preferred embodiment of the invention is disclosed for the purpose of imparting a clear understanding of the invention.

In the drawings:

Figure 1 is a fragmental side elevation of 50 my improved extractor partly in section as applied to the mouth of a bottle, and

Fig. 2 is a fragmental end elevation thereof of showing the arrangement of the operating jaw with relation to the piston rods and 55 cylinder.

Referring now more particularly to the

drawings, wherein like reference numerals refer to corresponding parts throughout the several views, we provide a pump cylinder indicating the same by the numeral 1, the lower portion of which is contracted as at 2, and then flared outwardly to constitute the substantially bell-shaped cap member 3. A bottom 4 is secured to the side walls of the cylinder 1 by means of a plurality of 60 screws 5 which are passed therethrough at a point adjacent the said contracted portions 2, and have arranged therein, preferably concentrically thereof, an opening 6, which serves to receive the suction controlled valve 65 7, the lower portion of which has attached thereto, a cross arm 7' whereby excessive upward movement of the said valve 7 will be prevented. It will be noted that the opening 6 is provided with a reduced portion, thus, forming an annular shoulder 8, consequently providing for means whereby the beveled portion of the valve 7 may be effectively seated thereupon. The upper end of the cylinder is open and normally receives thereover, a screw threaded cap 9, having an air exhausting opening 10 formed therein, for an obvious purpose. A piston head 11 having an opening 12 therethrough, which opening is normally closed by means 75 of a flap valve 13, is arranged interiorly of the cylinder and adapted for longitudinal movement therein. To provide for means whereby the piston head 11 may be moved, the rod 14 is secured to the upper face thereof and extends upwardly through a suitable opening arranged concentrically of the screw threaded cap 9 and has formed upon its upper extremity, an elongated bearing element 15, the purpose of which will be subsequently described. To provide for means whereby the neck of the bottle which we shall designate as "a," may be positively engaged with the sides of the cap member 3, thus affording an air tight connection, we 80 preferably line the same with a resilient material, such as rubber or the like, as at 16, it being obvious, that the same will permit the close engagement of the upper portion of the bottle neck a therewith and consequently, provide for the necessary connection.

In order to provide for means whereby the cylinder 1 may be supported during the operation thereof, we affix the same to the 110 outer end of the jaw member 17, which member is provided with handle portion 18,

and has arranged intermediate the ends thereof, an apertured lug 19. A second handle 20 is pivotally connected to the handle 18 by means of a pivot pin 21 which 5 is passed through the apertured lug and through a suitable opening formed in the adjacent end of said handle, the said handle 20 carrying thereupon, adjacent its pivoted portion, an upwardly curved arm 22 the 10 outer end of which is bifurcated to constitute the spaced apart arms 23 and 23', between which arms, journal a roller 24, supporting the same in position by means of the pivot pin 25 which is passed through 15 the arms 23 and 23'. It will be noted upon reference to Fig. 1, that the roller 24 is received within the slotted portion of the elongated bearing element 15 and permitted to travel therealong. Thus, when the upwardly 20 curved arm 22 is forced downwardly by means of the handle 20, the roller 24 will be moved forwardly in the elongated slot of the bearing element 15 until it has reached the opposite end thereof. Upon upward movement of the arm 22, the rod 14 and piston 25 head 7, will be drawn upwardly, the roller 24 moving in the elongated slot of said bearing element to its normal position. To provide for means whereby the arm 22 will be 30 normally held in its lowermost position, I secure thereto, a contractile coiled spring 26, engaging the lower portion of said frame with the lower portion 17.

In using my improved device, the flaring 35 cap portion is engaged with the neck of the bottle, thus causing an air tight connection therebetween, by means of the construction as heretofore described. Assuming that the arm 22 is in its lowermost position, the handle 20 is then depressed causing the said arm 22 to be moved upwardly, consequently drawing the piston rod 15 and the cylinder head upwardly within the cylinder 1 and consequently, moving the valve 40 45 7 from its seat 8, thereby creating a suction within the space below said piston. Should the stopper be but loosely seated within the mouth of the bottle neck, this suction as created will be sufficient to withdraw the same therefrom. However, in the event that the same is tightly sealed, the piston head 11 is then forced downwardly again, by means of the handle 20, whereupon, the flap valve 13 will be moved over 50 55 the opening and allow the air to escape through the exhaust 10 arranged within the closure cap 9, it being noted, that the valve 7 during this movement, has remained upon its seat, thus, closing the opening 5 and maintaining the vacuum within the cap 3. The piston head 11 is then drawn upwardly thus, exerting an additional pull 60 upon the stopper and causing the same to be dislodged from its seat within the bottle neck. It is of course understood, that the

suction may be increased in proportion to the number of strokes required to dislodge the cork from the bottle neck.

By forming the cap 3 substantially bell-shaped, it will be obvious that the device 70 may be adapted for use with bottles having various sized heads.

While we have herein disclosed the specific embodiment of the invention, it will be apparent to persons skilled in the art that the 75 invention is capable of embodiment in other forms and devices differing in detail and arrangement from that shown, as may be in keeping with the hereto appended claims.

Having thus described the invention, what 80 is claimed is:—

1. A stopper extractor, including a cylinder, the lower portion of said cylinder being contracted and provided with a flaring cap member increasing in size toward its outer 85 end, a valved partition arranged between the cylinder and said cap adjacent the contracted portion, a valve piston working within said cylinder, and means for operating said piston whereby to create a suction 90 in said cap when applied to a bottle neck for removing a stopper therefrom.

2. A stopper extractor, including a cylinder, the lower portion of said cylinder being contracted and provided with a flaring cap, 95 a valved partition arranged between said cylinder and said cap adjacent the contracted portion, a valved piston working within said cylinder, a resilient lining for said flaring cap, and means for operating said piston whereby to create a suction in said cap 100 when applied to a bottle neck for removing the stopper therefrom.

3. A stopper extractor, including a cylinder having a cap arranged upon the lower 105 portion thereof, a valved partition arranged between the cylinder and the cap, a valved piston working within said cylinder, a piston rod for said piston, the upper end of said rod provided with an elongated bearing 110 element, a handle affixed to said cylinder, a lever pivotally mounted upon said handle and having the outer portion thereof engaged with said elongated bearing element whereby the piston may be operated to create a suction in said cap when applied to a 115 bottle neck for removing a stopper therefrom, and resilient means connected to said handle and said lever for normally maintaining the piston in its lowermost position.

4. A stopper extractor comprising an elongated cylinder, said cylinder being contracted at its lower end to form a seat, a valved bottom secured to said seat, a flared bell projecting from said seat and increasing 125 in size toward its outer end, a valve piston head reciprocally mounted within said cylinder, a rod extending from said piston head and having a flat slotted frame at its outer end, a handle projecting outwardly from 130

- said cylinder, a second handle pivotally mounted upon said first mentioned handle and having means projecting through said flat slotted frame, whereby upon the movement of said last mentioned handle said rod will be reciprocated for causing a suction within said bell.
5. A stopper extractor comprising a cylinder, said cylinder having a flared bell projecting from its lower end, said bell increasing in size toward its outer end, a valve piston head reciprocally mounted in said cylinder, a rod extending from said piston head, and having a flat slotted frame at its outer end, a handle projecting outwardly from said cylinder, a second handle pivotally mounted upon said first mentioned handle and having means projecting through said slotted frame, whereby upon movement 10 of said last mentioned handles, said rods may be reciprocated for causing a suction within said bell.
15. A stopper extractor comprising an elongated cylinder, said cylinder being contracted at its lower ends to form a seat, a valved bottom secured to said seat, a flared bell projecting from said seat and increasing in size toward its outer end, a valve piston head reciprocally mounted within said cylinder, a rod extending from said piston head, a handle projecting outwardly from said cylinder, a second handle pivotally mounted upon said first mentioned handle, means connecting said last mentioned handle to said rod, whereby upon movement of 20 said last mentioned handle said rod will be reciprocated for causing a suction within said bell.
25. A stopper extractor comprising a cylinder having a flared bell projecting from its lower end, a valve piston head reciprocally mounted in said cylinder, a rod extending from said piston head, and having a flat slotted frame at its outer end, a handle projecting outwardly from said cylinder, a second handle pivotally mounted upon said first mentioned handle, means connecting said last mentioned handle to said rod, whereby upon movement of 30 said last mentioned handle said rod will be reciprocated for causing a suction within said bell.
35. A stopper extractor comprising a cylinder having a flared bell projecting from its lower end, a valve piston head reciprocally mounted in said cylinder, a rod extending from said piston head, and having a flat slotted frame at its outer end, a handle projecting outwardly from said cylinder, a second handle pivotally mounted upon said first mentioned handle, means connecting said last mentioned handle to said rod, whereby upon movement of 40 said last mentioned handle said rod will be reciprocated for causing a suction within said bell.

In testimony whereof we affix our signatures in presence of two witnesses.
